DISPENSER

George S. Light, Winsted, Conn.

Application October 10, 1940, Serial No. 360,597

8 Claims. (Cl. 312—73)

This invention relates generally to dispensers and more particularly to dispensers capable of dispensing fasteners, such as pins or nails, or other elongated forms of fasteners having enlarged heads.

Common pins are used extensively by garment manufacturers who manufacture wearing apparel such as men's shirts which are customarily folded and pinned in that condition to facilitate handling as well as to create a pleasing appearance. This pinning procedure presents problems for the reason that pin manufacturers package this type of pin in bulk whereby great difficulty is experienced in dispensing the pins in such a manner that personal injury to workers may be avoided and in such a manner that a great deal of wastage does not occur.

For lack of other dispensing means the garment manufacturing industry has been compelled to dispense pins in trays or boxes, the pins being more or less lumped together and not in any pre-arranged positions whatever. Thus the workers who use the pins are compelled to insert their hands within the trays or boxes to pick up one or several pins at a time with the result that frequent injuries occur, particularly to the fingertip of the workers.

Furthermore, under present manufacturing methods, considerable wastage of pins results from the attempts of the workers to meet production line speeds, it being impossible for a worker to grasp one pin at a time from a large mass of pins and at the same time attain the required speed of production. Consequently various habits are formed such as withdrawing a handful of pins from the bulk mass and spreading them upon the work table in order to facilitate selecting one pin at a time. According to common practice, shirts are pinned in certain places and passed along a table to another worker who inserts more pins in the garment, and as a result of this a considerable number of the pins which have been spread on the work table are brushed along the table until they ultimately fall on the floor or through cracks in the table. Although it is possible to recover such wasted pins, they are not usable for the reason that they become dirty or mixed with thread fragments or other foreign material.

Similar difficulties arise in other industries

where hand nailing is practiced, and therefore this invention is equally applicable where it is desirable to dispense nails of any size since they are in general of the same configuration as common pins.

Accordingly, the principal object of this invention is to provide a novel device for dispensing pins or other fastening devices of similar configuration which eliminates personal injury to the user, waste of such devices, and loss of time in obtaining such devices for use.

Another object of the invention is to provide a dispenser for delivering pins or other fasteners of similar configuration in such a manner that they may be grasped safely and in a uniform manner.

Still another object of the invention is to provide a pin dispenser which prevents access of dirt or other foreign matter to the pins and at the same time delivers the pins to a tray at a desired rate with predetermined relation to the user and to each other.

An additional object is to provide a dispenser for the purpose of dispensing fasteners such as pins or nails or any other form of fastener which comprises an elongated body portion and an enlarged head.

A further object is to provide a dispenser which is capable of dispensing and delivering fasteners of the type known as the "common" pin.

A still further object is to provide a dispensing device for delivering common pins or any other form of fastener having an elongated body portion and an enlarged head at a predetermined rate and in a predetermined relation to one another.

An additional object is to provide a pin dispensing device receiving pins in bulk form, separating them, and delivering them to a tray at a slow rate with the heads pointing uniformly in a single direction.

A still further object is to provide a dispensing device for delivering pins to a tray, the pins being substantially aligned and separated from one another with all of the heads pointing in a given direction.

Still another object is to provide a dispenser for delivering pins to a tray at a rate desired by the user.

Still another object is to provide a pin dis-

penser of simple mechanical design with as few moving parts as possible.

Further object and advantages of the invention will be apparent from consideration of the following specification taken in connection with the accompanying drawings, wherein:

Fig. 1 is a perspective of a pin dispenser constructed in accordance with the invention;

Fig. 2 is a plan view looking at the top of Fig. 1;

Fig. 3 is a fragmentary side view of Fig. 1;

Fig. 4 is a fragmentary side view of a modification of the invention;

Fig. 5 illustrates a modification of a delivery trough attached to the dispenser illustrated in Fig. 1; and

Fig. 6 is a side view of the same delivery trough as that disclosed in Fig. 5.

The preferred embodiment of this invention is illustrated in Fig. 1 of the drawings and comprises a tray or hopper 1 for receiving pins or other fasteners of similar configuration in bulk or an otherwise distributed mass, having a cover 2, a substantially rigid and vibration-transmitting standard 5 attached to a base portion 7, and a spaced apron 10 with a trough 12 attached thereto. The standard may be non-rigid if preferred. The hopper is preferably constructed of a metallic material of such thickness that the bottom portion 3 may vibrate in a manner somewhat similar to a diaphragm, the purpose of which is to impart a dancing motion to the pins contained in the hopper. The rear portion 4 of the hopper is secured to the standard 5 by means of any suitable securing means such as the bolt or screw 6. It is preferable that this fastening means be capable of providing or allowing motion of the hopper about its longitudinal axis whereby it may be leveled regardless of the level of the supporting means.

The bottom portion 3 of the hopper is closed at the forward end but is spaced from the rear portion 4 to allow the pins contained in the hopper to drop upon the apron 10. This form of construction also causes the bottom 3 to vibrate at greater amplitude at the point where the pins are about to drop to the apron.

The apron 10 is hinged to the standard 5 by means of the hinge 11 and is supported at the front end by the chain 13 which is made up of ball-like links attached to one another by straight rod-like links whereby the chain may be pulled through the circular aperture 14 until the apron 10 is in the desired sloping position, whereupon chain 13 may be inserted in slot 15 to retain apron 10 in fixed relation to the hopper. Other forms of adjustment may be used such as, for example, a screw connecting the hopper and apron. It is to be noted that apron 10 is spaced from bottom 3 of the hopper, the intervening space allowing the pins to separate from one another as they fall, whereby intermingled masses of pins do not collect on the apron.

Apron 10 is preferably constructed of a material such as pressed wood which has a roughened surface or a surface of considerable friction resulting from the fact that the wood fibers are somewhat separated from one another. This is an important feature of the invention as the friction causes a drag on the elongated portion of a pin while the weight of its head causes a rolling motion until the pin lies with its head facing down the slope of the apron. Thus all pins assume a uniform direction. It is not necessary that the surface be made of the above material as

it is also possible to utilize any form of base material covered with, for example, varnish which has been mixed with cotton fibers, rubber paint, canvas, or a layer of rubber. It is also possible to use a sand casting leaving the surface in the rough condition as it is taken from the mold, or steel having very fine grooves embossed therein. Any other surface having a slight amount of roughness or frictional characteristics such as those of the materials mentioned above can be used for this purpose. The apron is preferably slightly concave, to obviate the necessity of accurate leveling, and cut at its lower end 16 at a considerable angle, as illustrated in Fig. 1 of the drawings, whereby delivery chute 12 is sloped. The delivery chute 12 may be integral with the apron 10 or separately formed as an extension plate having a lip and attached to the apron as illustrated in the drawings. It is formed to comprise two surfaces, (1) which is parallel to that of the apron, and (2) which follows the arc of a circle tangent to the first surface portion. Thus as a pin slides down the surface of the apron, the head thereof is deflected by the curved portion of the chute, causing the pin to execute a turn into the chute in a predetermined position or direction. All pins execute the same motion and are therefore arranged in the chute with the heads pointing in a uniform direction. It is preferable that the bottom of the chute be slanted downwardly but it may be horizontal, as will be described in connection with Fig. 5. The delivery chute or trough 12 may be elongated in any desired manner to facilitate the delivery of pins.

20 The base portion 7 of the supporting structure is provided with a leveling device 8 which may be in the form of a screw and locknut as illustrated in Fig. 1. Thus the device may be mounted upon a supporting table or bench and adjusted by means of screw 8 to such a point that the bottom of the hopper 1 is level and then the base 7 may be securely fastened to the supporting table.

45 To operate the dispenser a tangled mass of pins is placed in the hopper 1 and delivery of pins occurs as a result of vibration of the hopper. The hopper may be vibrated by intermittently tapping it or the trough 12 which transmits vibrations through the standard 5 and chain 13. As it frequently happens that the table or other support on which the dispenser is fastened is caused to vibrate by machine operation within the room or building in which the table is located, manual striking of the hopper or trough may not be necessary. Hopper 1 may also be vibrated by operating switch 21 to energize solenoid 25 through battery 28 and cause striker 26 to tap the hopper. Vibrations, initiated by striker 26, or transmitted by the standard 5 or chain 13, will 50 cause the hopper and apron to vibrate in a substantially vertical plane, and the bottom of the hopper vibrates vertically at a comparatively high frequency with the greater amplitude near the hopper opening. When the tangled mass of pins 55 is placed in the hopper 1, it is preferable that the larger proportion of the pins rest at the front of the hopper and only a small portion of the pins lie at the hopper opening. Consequently when the hopper is vibrated, the greater amplitude of vibration near the hopper opening separates the pins lying at this point and they are jiggled or bounced from the main mass of pins and dropped upon the apron 10 being separated even more during the drop. The vibrations of the 60 bottom of the hopper 1 being of smaller ampli-

tude under the large mass of pins, they are moved slowly, but as each individual pin approaches the opening, the amplitude of vibration becomes greater and therefore speed of delivery is greater as the pin approaches the hopper opening. Thus the large mass of pins is slowly separated but prevented from moving steadily toward the hopper opening and a few pins at a time are jiggled or bounced until they drop to apron 10.

The frictional sloping surface of the apron 10 drags on the elongated shanks of the pins and causes them to roll into a head-down position after which they slide down the apron until they reach its edge, whereupon the slope of the trough causes the heads of all the pins to move along the trough facing in the same relative direction. Vibration of apron 10 is not necessary as it may be sloped until gravity causes the pins to slide. Thus the dispenser may be vibrated either mechanically or as a result of machine operation or by the operator striking the trough, and pins are delivered head foremost at any desired speed as determined by the amount of vibration and the adjustment of the chain which adjusts the slope of the apron.

It will be obvious that the dispenser will operate in the same fashion where it is desired to deliver other forms of fasteners such as nails of various sizes. If necessary, certain characteristics of the dispenser may be varied slightly to facilitate delivery of a particular size of nail.

Fig. 4 of the drawings illustrates another modification of the invention wherein the hopper 1 is reversed with respect to the apron 10. The dispenser is constructed in this manner if space facilities so require in the particular location in which the dispenser is to be used. This modification may be further changed by eliminating the space between the bottom 3 of the hopper 1 and the apron 10.

Figs. 5 and 6 illustrate a modified form of delivery trough 20, which is horizontal instead of sloping as illustrated in the preferred modification. This particular form of construction may be desirable where it is necessary to prevent pins from falling out of the trough as sometimes happens in the case of a sloping trough.

Various modifications of the apron 10 are possible. It may be constructed with a slight convex surface or a perfectly flat surface. These alternatives may be adopted if manufacturing methods or costs so require.

It will be obvious to those skilled in the art that further modifications are possible, and therefore it is desired that the invention shall be limited only by the appended claims and as required by prior art.

I claim:

1. A dispensing device comprising a base, a vertical standard attached thereto and so formed as to sustain vibratory motion, a hopper pivotally supported on the standard for receiving a mass of pins, an opening in the bottom of said hopper whereby vibratory motion of the standard and hopper will cause the contents of said hopper to drop through said opening, a sloping vibratory apron hinged to the standard in spaced relation to the bottom of said hopper for receiving said pins, a roughened surface on said apron for creating a drag on the shanks of the pins whereby they are caused to assume a position as they slide along the apron, a sloping delivery chute comprising an extension plate having an upturned lip attached to the lower edge of the apron, for deflecting and delivering the pins and causing

them to assume such a position that the heads face in a given direction and means for supporting the free end of said apron below said hopper.

2. A dispensing device comprising a base, a standard attached thereto and so formed as to transmit vibrations, a hopper supported on the standard for receiving a mass of pins, a slot in the bottom of said hopper whereby vibrations transmitted by the standard to the hopper will cause the contents of said hopper to drop through said slot, a sloping apron, a hinge supported by the standard and connected to said apron for spacing said apron below the bottom of said hopper, a rough surface on said apron for creating a drag on certain parts of the pins whereby they are caused to assume a given position as they slide along the apron, a delivery chute comprising an extension plate having an upturned lip attached to the lower edge of the apron for deflecting pins and causing them to assume a given position or direction and means connected between said apron and said hopper for adjusting the slope of said apron.

3. A dispensing device comprising a base, a standard on said base so formed as to sustain vibratory motion, a hopper supported on the standard, an opening in the rear, lower portion of said hopper whereby a certain degree of vibratory motion of the hopper will cause the contents of said hopper to drop through said opening at a certain rate, a sloping apron supported on the device in spaced relation to the bottom of said hopper and under said opening for receiving said contents and a continuous rough surface on said apron for creating a drag on certain parts of the individual articles comprising said contents whereby each of said articles is caused to face in a given direction as it slides along the apron.

4. A dispensing device comprising a base, a standard on said base so formed as to sustain vibratory motion, a hopper supported on the standard, an opening in the rear, lower portion of said hopper whereby a certain degree of vibratory motion of the hopper will cause the contents of said hopper to drop through said opening at a certain rate, a sloping apron supported on the device in spaced relation to the bottom of said hopper and under said opening for receiving said contents, a continuous rough surface on said apron for creating a drag on certain parts of the individual articles comprising said contents whereby each of said articles is caused to face in a given direction as it slides along the apron, a trough attached to the apron for collecting said contents and means for adjustably supporting said apron.

5. A dispensing device comprising a vibratable table support so formed as to sustain vibratory motion, a vibratable hopper on said support for receiving and discharging pins, an opening in the bottom of said hopper whereby vibratory motion of the hopper will cause the contents of said hopper to drop through said opening and an apron having an upper, concave, continuous, frictional, inclined surface supported on the device under said opening for intercepting the pins from the hopper and creating a drag on certain parts of individual pins whereby they are caused to assume a given position as they slide along the apron.

6. A dispensing device comprising a support, a flexible standard, means for securing said standard to said support, vibratable means on said standard for receiving and discharging pins, a sloping apron supported on the standard under

said vibratable means for intercepting the pins, a frictional surface on said apron for creating a drag on certain parts of the pins whereby they are caused to assume a given position as they slide along the apron, a delivery chute comprising an extension plate having an upturned lip attached to the lower edge of the apron, for collecting the pins and means adjacent said vibratable means for vibrating it.

7. In combination, a support, a flexible standard, means for securing said standard to said support, a vibratable hopper for receiving pins comprising a box structure mounted on said standard whereby the bottom of said box is free to vibrate, the bottom of said box having a slot therein whereby the portion of the bottom adjacent the slot may vibrate at a greater amplitude than other portions of the bottom to ad-

vance pins toward the slot at an increasing rate and separate the pins adjacent the slot and a sloping means comprising a rough surface supported on the standard under said hopper for delivering the pins as they drop through said slot.

8. In combination, means for discharging pins, a frictional, inclined conveying means under said discharging means for intercepting the pins, the lower edge of said conveying means describing an angle to the sides thereof, a delivery chute comprising an extension plate having a turned-up lip and attached to said lower edge whereby pins sliding along said conveying means are deflected uniformly thereby and assume a uniform position and a flexible standard for supporting said discharging and conveying means.

GEORGE S. LIGHT.
